Primary Examiner — Susan Moon Lee(74) *Attorney, Agent, or Firm* — Plumsea Law Group, LLC(57) **CLAIM**

The ornamental design for a toothbrush, as shown and described.

DESCRIPTION

FIG. 1 is a perspective view of a toothbrush showing my new design;

FIG. 2 is a rear perspective view thereof;

FIG. 3 is a rear elevational view thereof;

FIG. 4 is a front elevational view thereof;

FIG. 5 is a side elevational view thereof; and,

(Continued)

FIG. 6 is an opposite side elevational view thereof. The portions depicted in broken line illustrate parts of the toothbrush that form no part of the claimed design.

1 Claim, 6 Drawing Sheets
